UNITED STATES PATENT OFFICE.

CHARLES O. COZZENS, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

DESIGN FOR A TEMPLE FOR SPECTACLES.

Application filed May 19, 1923. Serial No. 6,226. Term of patent 14 years.

To all whom it may concern:

Be it known that I, CHARLES O. COZZENS, a citizen of the United States, residing at Southbridge, in the county of Worcester and State of Massachusetts, have invented a new, original, and ornamental Design for a Temple for Spectacles, of which the following is a specification, reference being made to the accompanying drawings, forming a part thereof.

Figure 1 is a perspective view of a temple for spectacle showing the ornamental design.

Figure 2 is a transverse sectional view on line *a—a* of Figure 1.

Referring to the drawings, it is to be understood that the temple is preferably made of metal or such material as is susceptible to a highly polished surface, and since the

temple is substantially triangular in cross section, it has longitudinal flat faces or facets, which cause reflections noticeably ornamental and distinctive to the eye. Though the temple as disclosed is manufactured and sold separately, it may, if it is so desired, be manufactured and sold in conjunction with spectacles.

What I claim is:

The ornamental design for a temple for spectacles, as shown.

In testimony whereof, I affix my signature in the presence of two witnesses.

CHARLES O. COZZENS.

Witnesses:

SUSAN CASAZZA,
ESTHER M. LAFLER.
